UNITED STATES PATENT OFFICE.

HENRY STAHL, OF CHERRY MILLS, PENNSYLVANIA.

HAY-FORK.

SPECIFICATION forming part of Letters Patent No. 292,378, dated January 22, 1884.

Application filed August 16, 1883. (No model.)

To all whom it may concern:

Be it known that I, HENRY STAHL, a citizen of the United States, residing at Cherry Mills, in the county of Sullivan and State of Pennsylvania, have invented certain new and useful Improvements in Hay-Forks; and I do hereby declare that the following is a full, clear, and exact description of the same, reference being had to the annexed drawings, 10 making a part of this specification, and to the letters and figures of reference marked thereon.

Figure 1 of the drawings represents a front elevation of my fork in its closed position; 15 Fig. 2, a similar view with the prongs extended, and Fig. 3 a side elevation.

This invention relates to certain new and useful improvements in hay-forks, and has for its object to improve the construction of this 20 class of devices, whereby a lighter, stronger, and more durable, as well as more readily operated, article of the kind may be obtained at a reduced cost, these objects being attained by the construction substantially as shown in 25 the accompanying drawings and hereinafter more fully described.

In the drawings, A represents the frame or casing of my improved fork, constructed, preferably, of steel in one continuous piece, bent 30 at the top to form a loop, a, to which the hoisting apparatus may be attached, this form of frame or casing giving the most strength for the amount of material employed.

Pivoted to the frame or casing A 35 are prongs B, a rivet, b, connecting the sides of said frame or casing just above these prongs, to prevent any springing out at this point.

Pivoted to the prongs B at points outside 40 of the pivotal connection of said prongs with the frame or casing A are side bars, C, which curve inwardly at their upper extremities, where they are pivoted to a central bar, D, and terminate each in an ear, c, which comes 45 against and slides upon the edge of one of the sides of said frame or casing when the central bar is operated, thus doing away with the necessity of slotting this bar or the sides of the frame or casing. The side bars, C, are 50 offset or bent laterally, as shown at d, and their lower portions are made narrower than

their upper, so that when the prongs B are either closed or opened the lower portion of said bars will rest against the edges of the frame sides, while the upper portions will be 55 incased therebetween. The rivet b not only prevents the frame or casing from becoming sprung, but also prevents the side bars, C, which are pivoted to the prongs B, from spreading apart laterally when said prongs 60 are extended and loaded.

To the upper end of the central bar, D, is pivotally connected a lever, E, having its bearing upon a pin, e, passing through it and the frame or casing A, said lever being 65 formed at its outer end with a loop, f, to which is attached a small rope for use in discharging the load, a stop, g, being placed between the sides of the frame or casing, to prevent said lever from coming too far over when 70 raised for throwing out the prongs B to engage the hay.

In the operation of my invention the fork is closed, as shown in Fig. 1, and forced down into the hay. The lever E is then raised 75 until it strikes the stop g. This raising of the lever causes the prongs B to spread, as shown in Fig. 2, thus engaging the hay, the prongs being locked in their extended position by means of the center bar, D, and lever 80 E, forming a toggle-joint, the three pivotal points of which assume a position a little beyond their dead-center, while the said lever comes against the stop g, and is there held, as before stated. The fork with its load is now 85 hoisted and conveyed to the point of discharge, where it is unloaded by pulling on the rope connected to the lever E, which breaks the lock and permits the prongs to assume their closed position ready for a repetition 90 of this operation.

Having now fully described my invention, what I claim, and desire to secure by Letters Patent, is—

1. The combination of the frame or casing 95 A, the prongs B, pivoted thereto, the lever E, also pivoted thereto, the side bars, C, provided with ears c, and the center bar, D, pivotally connected to said lever and said side bars, substantially as and for the purpose set forth. 100

2. The combination of the casing A, rivet b, stop g, lever E, prongs B, the laterally-bent

side bars, C, pivoted to said prongs, and having the narrow lower portions, and the inwardly-curved upper portions terminating in ears e, and the center bar, D, pivoted to said lever and said side bars, all arranged and operating substantially as and for the purpose described.

In testimony that I claim the above I have hereunto subscribed my name in the presence of two witnesses.

HENRY STAHL.
